CLAIM

The ornamental design for a folding table with pedestal base, as shown and described.

DESCRIPTION

FIG. 1 is a front perspective view of the folding table with pedestal base when in the collapsed condition;

FIG. 2 is a side perspective view of the folding table when in the collapsed condition of FIG. 1;

FIG. 3 is a top corner perspective view of the folding table when in its unfolded position of normal use; and,

FIG. 4 is a top front perspective view of the folding table when in the unfolded condition of FIG. 3.
